UNITED STATES PATENT OFFICE.

HARRY HAYES MEGARY, OF TORONTO, ONTARIO, CANADA.

HOSE-SUPPORTER.

1,291,062.

Specification of Letters Patent. Patented Jan. 14, 1919.

Application filed March 5, 1918. Serial No. 220,537.

To all whom it may concern:

Be it known that I, HARRY HAYES MEGARY, a citizen of the United States of America, and resident of the city of Toronto, county of York, Province of Ontario, in the Dominion of Canada, have invented certain new and useful Improvements in Hose-Supporters, as described in the following specification and illustrated in the accompanying 10 drawings, that form part of the same.

The principal objects of this invention are to devise a hose supporter in which the adjustable elastic band or the grip for holding the hose may be readily detached from the 15 connecting pad and renewed if desired, thereby enabling the wearer to renew either portion at will.

A further object is to devise a simple and inexpensive form of connecting pad which 20 will be extremely durable and comfortable to the wearer.

The principal feature of the invention consists in the novel construction and arrangement of parts, whereby the leg band 25 and hose supporting grip are individually detachably connected to a connecting pad.

In the drawing Figure 1 is a perspective view of my improved hose support. Fig. 2 is a vertical section through the lower fastening lug.

In the common forms of hose supporters of that type wherein the leg band and grip are connected to a pad, the elastic band is secured to the pad and when the elastic becomes worn or soiled and it may be desired 35 to change same the entire supporter is thrown away when the pad and grip may be perfectly good.

To avoid this waste I have devised the 40 present construction in which the pad 1 is preferably formed of sheet metal or a suitable fiber material or it may, if desirable, be made of textile fabric and is of triangular shape.

The pad is here shown formed of sheet 45 material having the lug members 2 punched therefrom and projecting outwardly from the face and formed with the T-shaped heads 3. The elastic band 4 is provided 50 with end loops 5 preferably formed of wire and having the converging sides 6. These loops are adapted to be hooked over the lugs 2, the heads engaging the converging sides and preventing the loops 5 from accidentally 55 slipping off.

The grip 7 for supporting the hose is of any desirable type having a metal loop 8 secured to the inner end. The pad is formed with a punched out lug member 9 which is adapted to receive the loop 8 and support 60 the grip.

The material of the pad is of a resilient nature and the punched out lug members are so formed that the head ends are turned slightly inward and the spring of the material prevents the accidental detachment of 65 the attached members.

If desired, the pad may be backed with a suitable lining of cork or other soft and preferably non-absorbent material in order 70 to prevent chafing or marking of the limb or underwear of the wearer. The pad may be made of textile material if desired and suitable lugs or catch devices secured thereon to take the place of the lugs 2 and 9 and 75 it will be readily seen that either the grip or the leg band may be quickly detached from the pad and any parts substituted that may be desired, without trouble.

A hose supporter such as described will 80 be extremely simple to manufacture and as both ends of the leg band are secured in a similar manner inconvenience of left and right will be eliminated.

What I claim as my invention is:— 85

1. A hose supporter, comprising a pad having fasteners arranged at each side of the top and an intermediately arranged fastener at the bottom, a leg band having the ends detachably engaging the top fasteners, 90 and a hose supporting member detachably secured to the lower fastener.

2. A hose supporter comprising, a pad formed of sheet material having lug projections punched outwardly therefrom at each 95 side of the top and a lug projection intermediately arranged below said side projections and forming a hook, a band having end loops adapted to slip over the upper projections, and a grip formed with a loop to engage the lower projection.

3. A hose supporter, comprising, a pad formed of sheet material having a pair of lug projections arranged one at each side of the top and formed with enlarged heads, a 105 single lug arranged at the bottom and spaced intermediate of the upper lugs, said lower lug being turned upwardly to form a hook, a band having convergent shaped loops arranged upon the ends adapted to engage 110

said upper lugs, and a fastening member having a loop adapted to engage the lower lug.

4. A hose supporter, comprising, a pad formed of sheet material having a plurality of lug projections punched therefrom, the outer ends of said lug projections being

turned inwardly and sprung toward the pad, a leg band formed of loops detachably secured to the upper pair of said lugs, and a fastening member having a loop detachably engaging the remaining lug. 10

HARRY HAYES MEGARY.
